UNITED STATES PATENT OFFICE.

THOMAS HANSBROW, OF SACRAMENTO, CALIFORNIA.

PUMP.

Specification of Letters Patent No. 31,314, dated February 5, 1861.

To all whom it may concern:

Be it known that I, THOMAS HANSBROW, of Sacramento, in the county of Sacramento and State of California, have invented a new and useful Improvement in Pumps; and I do hereby declare that the following is a full, clear, and exact description thereof, reference being had to the accompanying drawings, making a part of this specification, in which—

Figure 1, shows a perspective view of my pump and Fig. 2, is a vertical section of the same.

Similar letters of reference in both views represent corresponding parts.

To enable those skilled in the art to fully understand my invention, I will proceed to describe its construction and operation with reference to the drawing.

The pump-cylinder, A, is secured by means of a plate or ear, B, to a suitable board or standard. The plate, B, forms the bearing for the rock-shaft, C, which bears the cross-shaped piece, D. This piece forms two sockets, *a*, *a*, for the hand lever, E, and an arm, *b*, which connects by means of a pivot, *c*, with the sliding plate, F. Instead of this arm a toothed segment gearing into a rack cut into the under side of the plate, F, may be employed. This plate connects by means of an angular projection or standard, *d*, with the piston, G, so that by imparting an oscillating motion to the rock shaft, C, a reciprocating motion of the piston is produced. The water enters through the suction-pipe, H, into the valve-chest, I, which communicates with the interior of the cylinder through channels, *c*. The receiving-valves *f*, close down on the inclined seats, *g*, so that a small pressure is sufficient to raise the same, and

the water passes out through the discharge-valves, *h*, which close the apertures leading from the valve-chest to the air-vessel, J.

The air-vessel is secured to the top of the valve-chest by means of stirrups, K, which are pivoted to the sides of the valve-chest, so that on releasing the set-screws, *i*, said stirrups can be turned down, and the air vessel can now be easily removed. The water rises in the air-vessel, and it discharges through the spout M.

By having the inclined valves arranged above the cylinder, any sand or other solid substances that may be drawn in by the pump, are prevented from lodging on the inclined valves or their seats, and thus the pump is prevented from becoming inoperative. The valves are also, by this arrangement kept tight, so that the charge of water, necessary to operate the pump cannot escape.

By the sliding plate arrangement, to work the piston the latter is not only operated but is guided in a straight line.

I do not claim broadly the use of inclined valves and valve seats, but,

Having thus described my invention, what I claim as new and desire to secure by Letters Patent is:—

The arrangement of the inclined valves *f*, seat *g*, and suction pipe H above and with the cylinder A and piston G in combination with the sliding guide plate F and oscillating armed lever receiving piece D in the manner and for the purposes herein shown and described.

THOMAS HANSBROW.
